DESIGN FOR A ROTARY VENTILATOR

James H. McDerment, Cleveland, Ohio, assignor
to The Swartwout Company, Cleveland, Ohio,
a corporation of Ohio

Application November 10, 1937, Serial No. 72,755

Term of patent 14 years

To all whom it may concern:

Be it known that I, James H. McDerment, a citizen of the United States, residing at Cleveland, in the county of Cuyahoga and State of Ohio, have invented a new, original, and ornamental Design for a Rotary Ventilator, of which the following is a specification, reference being had to the accompanying drawing, forming part thereof,

wherein Fig. 1 is a side elevation, Fig. 2 a top plan view, and Fig. 3a a front elevation of a rotary ventilator showing my new design.

I claim:

The ornamental design for a rotary ventilator, substantially as shown.

JAMES H. McDERMENT.
